United States Patent Office.

GARDNER CHILSON, OF BOSTON, MASSACHUSETTS.

Letters Patent No. 75,665, dated March 17, 1868.

IMPROVEMENT IN COOKING-STOVES.

The Schedule referred to in these Letters Patent and making part of the same.

TO ALL PERSONS TO WHOM THESE PRESENTS MAY COME:

Be it known that I, GARDNER CHILSON, of Boston, in the county of Suffolk, and State of Massachusetts, have invented a new and useful Improvement in Cooking-Stoves; and do hereby declare the same to be fully described in the following specification, and represented in the accompanying drawings, of which—

Figure 1 is a longitudinal and vertical section of a stove provided with my invention.

Figure 2 is a transverse section, and

Figure 3 is a horizontal section taken through the fireplace.

Figure 4 is a front elevation, and

Figure 5 is a horizontal section, taken through the boiling-chamber or main upper flue of the stove.

In such drawings, A denotes the fireplace, B the grate, *a a* and *b* the soapstone jambs of the fireplace, C the oven, D the ash-chamber, E the boiling-chamber, and F the flue leading therefrom and about the oven, the whole being arranged in manner as represented.

In stoves and cooking-ranges, it has been customary to locate the "hot-water back" or water-heater at the rear of the fireplace, or between it and the oven.

In carrying out my invention, I arrange the hot-water heater at the front of the fireplace and its jambs, whether the latter be of soapstone or fire-brick. In the drawings, the said water-heater is represented at H as arranged in front of the fireplace and its jambs, and between the same and an air-space or insulating-chamber, G, provided with an opening at its front, and one or more doors, *d d*, for closing such opening. From this water-heater two pipes, *e e*, lead backward, directly over the end-jambs of the fireplace, and through and beyond the boiling-chamber E. These pipes are to convey water into and from the water-heater, the water to be heated going through one pipe, and being discharged from the vessel by the other, and into an elevated cistern, such as commonly employed with stoves and ranges provided with "water-backs." At each end of the fireplace, and against its end-jamb, is an insulating air-chamber, I. It serves to prevent the heat of the fireplace, conducted through the jamb, from being lost through the side-plate *f* of the stove. K is an air-register, for supplying air to the grate and fireplace. L L are the ash-chamber doors.

The improved arrangement of the water-heater is advantageous in several respects: First, it enables the oven to be heated to better advantage than it is likely to be when a water-back is employed between it and the fireplace; second, it is a protection to a person standing in front of the stove, as it insulates such person from the fuel, and being at a temperature not greater than that of boiling water, it cannot set fire to the clothes of a person. The air-chamber in front of the water-heater operates to prevent loss of heat therefrom by radiation. Within the said air-chamber, and applied to the lower part of the water-heater, is a discharge-cock, M, which serves to enable a person to draw water from the heater, or to discharge any sediment deposited therein. By arranging the water conduits within the boiling-chamber, and with respect to the fireplace, in manner as specified, the water, while passing through them, will be heated by the heat and volatile products of combustion contained in the said chamber.

I do not claim the arrangement of a water-heater or "water-back" at the rear part of the fireplace, or between the fireplace and oven; nor do I claim the extension of a water-heater entirely around a fire-pot of a furnace or stove; nor do I claim the mere extension of the pipe of a water-heater through what is usually termed boiling-chamber of a stove, viz, the flue-space leading from the fireplace and over the oven.

I claim as my improvement—

The arrangement of the water-heater, the oven, and the jambs of the fireplace, the said jambs, under such arrangement, being between the oven and the heater, and the latter being at the jamb of the fireplace, as set forth.

I also claim the combination and arrangement of the insulating air-chamber and its door-opening, and the door or doors thereof, with the water-heater, arranged in front of the fireplace in manner as explained.

GARDNER CHILSON.
